ASSEMBLER FOR LINE CASTING MACHINES

Einar Erik Alm, Stockholm, Sweden

Application January 5, 1944, Serial No. 517,101
In Sweden February 5, 1941

6 Claims. (Cl. 199—29)

1

This invention relates to an assembler for line casting machines, comprising two parallel matrix assembling rails located at different levels, the rail located at the higher level being displaceable along its own plane and consisting of two parts, one of said parts being in the form of a slide displaceable along said last named rail in a manner such that in one end position said slide being adapted to receive matrices, while in its other end position it permits matrices of falling down and remaining in an upright position on the lower rail.

The invention has for its object to facilitate alternate setting up of different characters and to render possible transition from one type of characters to another one by actuating a single lever without the necessity of manual displacement of matrices and without necessity for the operator to pay particular attention to the assembler when shifting from one type of characters to the other one.

This and further objects, I attain by mechanism illustrated in the accompanying drawings, in which—

Fig. 1 is a front elevation of the assembler; Fig. 2 a side elevation of the assembler with the upper rail out of engagement, viewed from the right of Fig. 1; Fig. 3 a view similar to Fig. 2 with the upper rail in operative position; Fig. 4 a plan view of the assembler with the upper rail in the position shown in Fig. 2; Fig. 5 a plan view of the assembler with the upper rail in the operative position according to Fig. 3; Fig. 6 a plan view of the assembler with the slide in a displaced position for setting up roman characters; Fig. 7 a similar view with the parts in a position which should not be used during the setting up operation; Figs. 8-11 part of the assembler with different positions of the slide for setting up roman and italic characters in an alternate manner; and Fig. 12 a view illustrating the movable connection between one end portion of the slide and the appertaining rail.

Referring to the drawings, the frame 1 of the matrix assembler is made integral with a fixed rail 2 for the roman position of the matrices. Above and parallel to the rail 2 there is located a movable rail 4 for assembling matrices in the italic position, said rail 4 being disposed between the frame 1 and a plate 3 secured to the frame. The rail 4 is displaceable along its own plane by means of a lever 7 which together with arms 6 and 8 is mounted on a shaft 9, the lever 7 and the arms 6 and 8 being movably connected with the upper rail 4. By turning the lever 7,

2

the rail can be brought either into the inoperative position shown in Figs. 2 and 4 or into the operative position shown in Figs. 3 and 5.

In accordance with this invention, that portion of the upper rail 4 on which matrices may be collected, is in the form of a slide 5 displaceable to and fro along the rail 4. To this end, an arm 13 provided with a lever 12 is mounted on a pin 11 secured to the rail 4, said arm 13 being adapted to engage a projection 14 of the slide 5. A torsional spring 22 wound around the pin 11 serves to keep the arm 13 in its proper positions. When the lever 12 is turned to the right from the position shown in Fig. 5, the arm 13 will be turned such as to permit the slide 5 of being displaced towards the left into the position shown in Fig. 6. Said displacement which is assisted by a spring 15 inserted between the members 4 and 5, takes place substantially through the action of matrices as they are set up, as will be more clearly described hereinbelow. When the lever 12 is turned back into the position shown in Fig. 5, the arm 13 acts upon the projection 14 such as to displace the slide 5 into the position shown in Fig. 5. At the displacement of the slide 5, a thinned end portion 16 thereof will slide above a correspondingly lowered face 17 of the rail 4 (Fig. 12). With the parts in the positions shown in Fig. 5, said thinned end portion 16 constitutes a bridge over the space between the members 4 and 5 and thereby prevents matrices assuming italic positions from falling down into roman positions. At the opposite end, the slide 5 has an upwardly projecting lip 18 on the inside of which the matrices are falling down as they are being set up. In the position shown in Figs. 2 and 4, the lip 18 is located in a recess 23 provided in the plate 3. The rail 4 has a similar lip 24 which in the position according to Figs. 3 and 5 is disposed in the recess 23 and thereby prevents thin matrices from getting stuck in the recess, which otherwise might occur when the slide 5 begins to move towards the position according to Fig. 6. Below the thinned portion 16, the slide 5 has a projection 25 engaging a recessed portion 29 provided in the rail 4, as will be seen from Figs. 4-7. The last-named projection and recess in connection with the other abutting places between the slide 5 and the rail 4 serve as a guide for the slide together with the tension of the spring 15. As shown in Fig. 7, said guide means permit a certain turning movement of the slide 5 out of its parallel position with respect to the rail 4. Said turning movement will occur when the rail 4 is moved into its inoper-

ative position without the lever 12 having been swung into the position shown in Fig. 4. In this case, the lip 18 is stopped in contact with the plate 3 and prevents the right hand end of the slide 5 from moving together with the remaining portion of the rail 4. When the lever 7 forces the rail 4 into the position according to Fig. 7, a positive movement of the slide 5 might be liable to damage the lip 18 as the same is forced against the plate 3. This inconvenience is eliminated by the slide 5 having a certain possibility of turning movement. In the position shown in Fig. 7, the assembler should not be operated. If the lever 12 is moved to the left from the position according to Fig. 7, the slide 5 returns to the position shown in Fig. 4 with the lip 18 located in the recess 23 of the plate 3. This movement is facilitated by the pressure of the arm 13 against a shoulder 26 at the projection 14. On the lower side of the plate 3, there is provided a recess 27 which in such a manner cooperates with a pin 28 in the slide 5, that the forward edge of said slide due to an excessive turning movement will not be forced into the assembler to a greater extent than that shown in Figs. 3 to 7, that is, the movement of the slide in the direction of the movement of the rail 4 is limited by said pin and recess. A lip 19 having a similar purpose as the lip 18 is secured to the fixed rail 2. To the right of said lips 18 and 19, as viewed in Figs. 8 to 11, there is provided a rotatable star wheel 20 the arms of which actuate the matrices one after the other so as to force the same inwardly and downwardly into the assembler, as they are set up. The first matrix in the series abuts against a slidable support 21.

The device described above operates in the following manner. In order to set up matrices in roman positions only, the upper rail 4 is shifted to its inoperative position according to Figs. 2 and 4, while its position according to Figs. 3 and 5 corresponds to the italic position. In order alternately to set up roman and italic characters, the operation may be started with the rail 4 in the position shown in Figs. 3 and 6. Matrices entering the assembler will, in this position, not be hindered by the rail 4 and the slide 5 from assuming roman positions, as shown in Fig. 8. If it is desired to change from roman to italic position, the lever 12 is swung into the position shown in Fig. 5 with the result that the matrices will be placed on the rail 5 assuming italic position, as shown in Fig. 9; each matrix then being fed into the clearance between the lip 18 and the preceding matrix by means of the star wheel 20. In order to shift over to roman position, the lever 12 is swung into the position according to Fig. 6. Due to the fact that matrices are present on the rail 4, the slide 5 can not immediately assume the position according to Fig. 6, since the lip 18 will abut against the last matrix set up in italic position so as to stop the movement of the slide 5, said movement being not greater than the sum of the clearances which might be formed between the last matrices set up in the series, as will be seen from Fig. 10. The next matrix which enters the assembler will as usually abut against the preceding matrix in the italic position. The star wheel 20 feeds the matrix into the assembler as long a distance as usual. However, since the lip 18 at that time due to the spring 15 abuts against the last matrix set up in italic position and thus follows the movement of said matrix, the matrix entering the assembler will slide downwardly into roman position outside the lip

18, as indicated in Fig. 11. Due to the fact that the body of each matrix as a rule is wider than that portion thereof against which the lip 18 abuts, certain clearances will be formed, as shown in Figs. 8 to 11, said clearances facilitating the sliding movement of the matrix beyond the lip 18, which to this end may be somewhat bevelled, as shown in the drawing. It occurs, however, very seldom that matrices are abutting each other at the place between roman and italic positions. Frequently, a clearance is formed at that place between two words by means of a justifying wedge which absolutely ensures that the next following matrix will assume its proper position.

It will be understood that the invention is not limited to the construction described above which may be modified in various ways without departing from the spirit of the invention.

What I claim is:

1. An assembler for line casting machines comprising a fixed matrix assembling rail, a second matrix assembling rail including a plate member and a slide carried thereby for longitudinal movement, means supporting said second rail for lateral movement between a retracted position and a projected operative position in which said slide is over said first rail, and means for moving said slide longitudinally between a matrix receiving position and an inoperative position when said second rail is in projected position; said last means comprising an arm mounted on said plate member for pivotal movement to displace the slide in one direction and a spring for displacing the slide in the opposite direction.

2. An assembler for a line casting machine as recited in claim 1 wherein said spring tends to retain the slide in inoperative position, and said arm moves said slide positively into matrix receiving position.

3. An assembler for a line casting machine as recited in claim 1, wherein the slide has an upwardly projecting lip constituting an abutment for the matrices, and said supporting means includes a fixed plate above said second rail, said fixed plate having a recess for receiving said slide lip when said second rail is moved into retracted position, and said plate member of the second rail has a lip extending across the entrance to the recess when said second rail is in projected position.

4. In an assembler for a line casting machine, the combination with a stationary frame having a slot therethrough above a fixed matrix assembling rail, of a movable rail slidably mounted in said slot; said movable rail comprising a plate member supported in said slot for lateral movement between a retracted position and a projected operative position, a slide movable laterally with said plate member in said slot and movable independently of said plate member in a longitudinal direction; and manually operable means carried by said plate member for moving said slide longitudinally.

5. In an assembler for a line casting machine, the invention as recited in claim 4 wherein said plate member is cut back from its inner edge to provide a recess in which the slide is arranged, the upper surface of said slide being substantially flush with that of the plate member, and said plate member and slide having thin guide portions overlapping at the matrix discharge end of the rails to form a bridge for the transfer of matrices from the slide to the plate member.

6. In an assembler for a line casting machine, the invention as recited in claim 4 wherein said

plate member is cut back from its inner edge to provide a notched recess in which said slide is loosely arranged, said slide having a portion extending into the notch of said plate member recess to connect the slide to the plate member for lateral movement thereby and for independent longitudinal movement.
